ARC CHUTE UTILIZING INTERLEAVED
U-SHAPED CONDUCTIVE MEMBERSAlvin E. Herman, Milwaukee, Wis., assignor to
Allis-Chalmers Manufacturing Company, Mil-
waukee, Wis.

Application June 29, 1950, Serial No. 171,074

5 Claims. (Cl. 200—144)

1

This invention relates in general to arc extinguishing means and in particular to arc chutes associated with electric switching devices.

It is a principal object of this invention to provide an arc extinguishing structure in which series connected arcs are successively drawn and each of the arcs is subsequently broken into a plurality of divided arcs.

It is an additional object of this invention to provide an improved arc extinguishing chute in which the arc current traverses a path of increasing resistance as the arc travels in the chute.

It is a further object of the present invention to provide an arc extinguishing chute assembly which is compact, rugged and easily detached from the switching device.

Objects and advantages other than those outlined above will be readily apparent from the following detailed description when read in connection with the accompanying drawings, in which:

Fig. 1 is a side view, partly broken away, of a switching device embodying the present invention;

Fig. 2 is a sectional view taken along line II—II of Fig. 1;

Fig. 3 is a side view of the arc chute assembly of the present invention, with one side wall removed;

Fig. 4 is a sectional view taken along line IV—IV of Fig. 3;

Fig. 5 is a development view on an enlarged scale looking in the direction of arrow V of Fig. 3;

Fig. 6 is a perspective view of a component element of the arc chute assembly;

Fig. 7 is an end view of an alternate embodiment of a component element of the arc chute assembly;

Figs. 8, 9 and 10 are diagrammatic views along a median plane of the arc chute illustrating successive steps in the operation of the arc chute of this invention as the contacts of the switching device separate.

Referring to the drawings, a switching device embodying the present invention comprises a pair of relatively movable contacts 11, 12 between which an arc may be formed upon separation thereof. The arc may be drawn in any suitable insulating fluid, such as air at atmospheric pressure. Contact 11 is connected through a curved conductive bar 13 to a terminal stud 14, while contact 12 is connected through a conductive member 15 and a flexible lead 16 to a terminal stud 17. Studs 14, 17 represent connections to a circuit which the switching device is to interrupt.

The fixed contact assembly is secured to a suit-

able insulating base 18 by nuts 19 engaging terminal studs 14 and by a bracket 22 secured to bar 13 by a bolt 23, while stud 17 is secured to base 18 by nuts 20. Secured to bar 13 by rivets 27 is a U-shaped bridging member 28 of laminated magnetic material which has a pair of laminated pole plates 31, 32 secured to its legs by rivets 33. Bar 13 acts as a blowout coil in a well known manner, in cooperation with member 28 and plates 31, 32, to accelerate the travel of the arc formed upon separation of contacts 11, 12 into the arc extinguishing chute. The additional blowout action provided by bar 13, member 28 and plates 31, 32 may be dispensed with if the heat generated by the arc is sufficient to impel the arc upwardly in the chute.

Contact 12 is movable into and out of engagement with contact 11 by movement of a shaft 36. Shaft 36 is journaled in brackets 37 secured to base 18 by screws 38 and is given rotational movement by suitable actuating means (not shown) such as an electromagnet. Shaft 36 is provided with an octagonal portion 39 having an insulating coating 41. Around octagonal portion 39 is secured a clamp comprising a pair of clamping members 42, 43 secured together by screws 44. Clamping member 42 is provided with an extension forming a finger 46 bearing against member 15 and providing a pivot about which member 15 and contact 12 may turn. A plate 45, of suitable known hard material such as stainless steel, is provided to furnish a wearing surface for finger 46. Flexible lead 16 is clamped against nut 20 and stud 17 by a nut 24.

A stud 47 extends with clearance through an aperture in member 42 and is secured to member 15 and flexible lead 16 by a nut 48. A spring 49 compressed between finger 46 and a nut 51 pulls against member 15 and urges contact 12 to the closed position shown when finger 46 is in the position shown. Nuts 51 may be adjusted to vary the pressure between contacts 11, 12.

When shaft 36 is rotated clockwise from the position shown, finger 46 also rotates clockwise and enables spring 49 to pull member 15 and contact 12 to the right, thereby separating contacts 11, 12 and causing an arc to be formed between the contacts. The heat generated by formation of the arc impels the arc to rise into the arc extinguishing chute 55, and an additional impelling force may be given to the arc by the blowout assembly comprising bar 13, member 28 and plates 31, 32.

As best shown in Figs. 3 to 5, the arc chute 55 comprises a pair of spaced side walls 56, 57 lo-

cated on opposite sides of the path of movement of the arc. Chute 55 is provided with an intermediate section 53 adjacent contacts 11, 12 wherein the arc is formed and an exhaust section 54 between the top portions of the side walls 56, 57. Two pluralities of U-shaped conductive members 58a through 58f and 59a through 59f are secured to side walls 56, 57, respectively, and form two interleaved rows disposed in the general lengthwise direction of the arc. Members 58, 59 may be made of any suitable heat resistant conductor such as steel or brass. As shown in Fig. 6 which illustrates a representative member, 58b, each conductive member 58, 59 comprises a pair of spaced leg portions 61, 62 extending in the general direction of travel of the arc and a curved portion 63 joining the leg portions 61, 62 in the intermediate section of the chute. The distance between adjacent leg portions of adjacent conductive members may be of any suitable value but preferably increases from the intermediate section to the exhaust section of the chute 55, as shown in Fig. 3. The distance between leg portions 61, 62 may be constant or, as shown in Fig. 3, may be greatest at the bight of U and decrease as the leg portions approach the exhaust section of the chute.

Members 58, 59 abut their respective side walls along an edge extending from the bight of the U to the exhaust section of the chute. Some of the conductive members 58, 59, and preferably all of them, increase in depth in a direction perpendicular to the direction of movement of the arc and to the lengthwise direction of the arc, i. e. away from the side wall to which they are secured and toward the opposite side wall, from the bight of the U, and are adjacent to or abut the opposite side wall at the exhaust section of the chute. This increase in depth of members 58, 59 forms edges 60 on members 58, 59 upon which the arc impinges during its movement in chute 55. As shown in the drawing, members 58, 59 may be set in recesses 64 in their respective side walls 56, 57, and if members 58, 59 abut the opposite side wall at the exhaust section of the chute, recesses 65 may be provided to receive the abutting ends.

Insulating end members 66, 67 are provided to maintain the proper spacing of side walls 56, 57, and to cooperate with the side walls to confine the arc. The entire arc chute assembly is rigidly secured together by rivets 68 extending through walls 56, 57 and members 66, 67. A bracket 71 secured to bridging member 28 by rivets 72 is provided to removably mount the arc chute assembly with respect to contacts 11, 12. Projecting fingers 73 of bracket 71 engage a pair of recesses 74, 75 in side walls 56, 57 when the arc chute assembly is lowered to the position shown in Fig. 1. Figures 73 abut stepped portions 76, 77 of side walls 56, 57 above recesses 74, 75 to thereby detachably secure the chute assembly. Pole plates 31, 32 engage recesses 78, 79 in side walls 56, 57 and abut the side walls above these recesses to provide additional support for the arc chute assembly.

Upon separation of contacts 11, 12, an arc is formed therebetween in the intermediate section of chute 55. The heat generated by this arc impels the arc upwardly in chute 55, and the blowout assembly described above furnishes additional impelling force. As shown in Figs. 8 and 9, the arc in moving upward first impinges on conductive member 58a between contact 11 and member 58a, and as contact 12 continues to

move, the arc is extended until it impinges on member 58b. At this time, the arc will exist in the form of short arc 81 between contact 11 and member 58a, another short arc 82 between adjacent leg portions of members 58a and 58b, and another short arc 83 formed between member 58b and contact 12. Continued movement of contact 12 causes the arc to successively impinge on the succeeding conductive members 58c, 58d, 58e, 51f, thereby successively drawing a plurality of short arcs between adjacent leg portions of adjacent conductive members. These short arcs rise in chute 55 and the arc current between the plurality of short arcs traverses the leg portions and curved portions of conductive members 58. As the short arcs move toward the exhaust section of the chute, the distance between adjacent leg portions of adjacent members 58 increases, thereby increasing the resistance of the air gaps through which the short arcs travel, and hence reducing the magnitude of the arc current and hastening the extinction of the arc. In addition, the arc current flowing in the conductive leg portions meets a path of continually increasing resistance owing to the increasing distance in the conductive members through which this current must flow. This increasing resistance further progressively reduces the arc current and thereby further speeds the extinction of the arc.

The arc current flowing in the conductive members 58 produces magnetic fields about members 58 which force the arc toward the exhaust section of the chute. Referring to Fig. 6, arcs impinging on leg portions 61, 62 cause a current to flow therein, for example downwardly in leg 62, as indicated by arrow 86, and upwardly in leg 61, as indicated by arrow 87. The current represented by arrow 86 produces about leg 62 a field represented by flux line 88, while the current represented by arrow 87 produces about leg 61 a field represented by flux line 89. The field represented by flux line 88 acts on the short arc existing between leg 62 of member 58b and the adjacent leg of member 58a and forces this short arc upward toward the exhaust section of the chute. Likewise the field represented by flux line 89 forces the short arc existing between leg 61 of member 58b and the adjacent leg portion of member 58c toward the exhaust section of the chute. This blowout action produced by the arc current traversing members 58 considerably hastens the travel of the arc toward the exhaust section of the chute where the arc is eventually extinguished.

When the short arcs are in the intermediate section 53 of the chute, only the members 58 of side wall 57 are effective in extinguishing the arc. However, when the arcs approach the exhaust section of the chute, the arcs encounter the leg portions of conductive members 59, which increase in depth in a direction toward side wall 57 from the bight of the U. As shown in Fig. 10, the arc 82 existing between adjacent leg portions of members 58a, 58b, upon reaching the exhaust section of the chute, is split into two divided arcs, one such divided arc 91 existing between adjacent leg portions of members 58a, 59a, while the other divided arc 92 exists between adjacent leg portions of members 59a, 58b. The arc current now flows through member 59a and produces magnetic fields about the legs of this member similar to those produced by the arc current in member 58b tending to extinguish the 75 arc. The action of the other members 59 as the

shorter arcs reach the exhaust section of the chute is similar to that described above for member 59a and the combined field produced by the current in all of the members 58, 59 is now increased with respect to the field produced when the arc current traversed only members 58, thereby greatly speeding the extinction of the arc in the exhaust section of the chute.

Although in the above described operation of the arc chute, it was assumed that the arc impinged on member 58a upon separation of contacts 11, 12, it will be readily apparent that the arc might impinge on member 59a upon separation of the contacts and then be caused to successively impinge on members 59b, 59c, 59d, 59e, 59f, without changing the principle of operation of the arc extinguishing means.

In the alternate embodiment of the U-shaped conductive member illustrated in Fig. 7, the leg portions 93, 94 of the member extend substantially parallel to each other from the bight of the U to the exhaust section of the chute. The operation of arc chute provided with conductive members of the type shown in Fig. 7 is identical to that above described with respect to the arc chute illustrated in Figs. 1 to 6.

Although but two embodiments of the invention has been shown and described, it will be apparent to those skilled in the art that various modifications may be made therein without departing from the spirit of the invention or from the scope of the appended claims.

It is claimed and desired to secure by Letters Patent:

1. Means for extinguishing an electric arc movable in a predetermined direction comprising an arc chute provided with a pair of spaced side walls located on opposite sides of the path of movement of said arc and having an intermediate section wherein said arc is formed and an exhaust section, and a plurality of U-shaped conductive members on which different portions of said arc successively impinge, said members being secured to said side walls and forming two interleaved rows disposed in the general lengthwise direction of said arc, each said member comprising a pair of spaced leg portions extending in the general direction of movement of said arc and having a curved portion joining said leg portions in said intermediate section of said chute, each of said leg portions of each of said members abutting one of said walls in said intermediate section of said chute and increasing in depth in a direction perpendicular to said directions from said intermediate section to said exhaust section.

2. Means for extinguishing an electric arc movable in a predetermined direction comprising an arc chute provided with a pair of spaced side walls located on opposite sides of the path of movement of said arc and having an intermediate section wherein said arc is formed and an exhaust section, and a plurality of U-shaped conductive members on which different portions of said arc successively impinge, said members being secured to said side walls and forming two interleaved rows disposed in the general lengthwise direction of said arc, each said member comprising a pair of spaced leg portions extending in the general direction of movement of said arc and having a curved portion joining said leg portions, the distance between adjacent leg portions of adjacent members increasing from said intermediate section of said exhaust section, each of said leg portions of each of said members

abutting one of said walls in said intermediate section of said chute and increasing in depth in a direction perpendicular to said directions from said intermediate section to said exhaust section.

3. Means for extinguishing an electric arc movable in a predetermined direction comprising an arc chute provided with a pair of spaced side walls located on opposite sides of the path of movement of said arc and having an intermediate section wherein said arc is formed and an exhaust section, and a plurality of U-shaped conductive members on which different portions of said arc successively impinge, said members being secured to said side walls and forming two interleaved rows disposed in the general lengthwise direction of said arc, each said member comprising a pair of spaced leg portions extending in the general direction of movement of said arc and having a curved portion joining said leg portions in said intermediate section of said chute, the said members secured to one of said walls abutting said one wall in said intermediate section and increasing in depth in a direction toward the opposite said wall in said intermediate section of said chute and abutting said opposite wall at said exhaust section of said chute.

4. Means for extinguishing an electric arc movable in a predetermined direction comprising an arc chute provided with a pair of spaced side walls located on opposite sides of the path of movement of said arc and having an intermediate section wherein said arc is formed and an exhaust section, and a plurality of U-shaped conductive members on which different portions of said arc successively impinge, said members being secured to said side walls and forming two interleaved rows disposed in the general lengthwise direction of said arc, each said member comprising a pair of substantially parallel spaced leg portions extending in the general direction of movement of said arc and having a curved portion joining said leg portions in said intermediate section of said chute to form a U, the said members secured to one of said walls abutting said one wall in said intermediate section and increasing in depth in a direction toward the opposite said wall from the bight of said U and abutting the opposite said wall at said exhaust section of said chute, the said members secured to one of said walls being staggered with respect to the said members secured to the other said wall in said intermediate section of said chute and said members secured to said one wall overlapping said members secured to said other wall in said exhaust section of said chute.

5. Means for extinguishing an electric arc movable in a predetermined direction comprising an arc chute provided with a pair of spaced side walls located on opposite sides of the path of movement of said arc and having an intermediate section wherein said arc is formed and an exhaust section, and a plurality of U-shaped conductive members on which different portions of said arc successively impinge, said members being secured to said side walls and forming two interleaved rows disposed in the general lengthwise direction of said arc, each said member comprising a pair of spaced leg portions extending in the general direction of movement of said arc and having a curved portion joining said leg portions in said intermediate section of said chute to form a U, each of said members secured to said walls abutting said one wall in said inter-

mediate section and increasing in depth in a direction toward the opposite said wall from the bight of said U and abutting the opposite said wall at said exhaust section of said chute, the said members secured to one of said walls being staggered with respect to the said members secured to the other of said walls in said intermediate section of said chute and said members secured to said one wall overlapping said members secured to said other wall in said exhaust section of said chute. 10
